Primary Examiner — Amy C Wierenga*Assistant Examiner* — Andrea Marie McKay(74) *Attorney, Agent, or Firm* — Sam IP Legal Solutions, P.C.; Ryan D. Sam(57) **CLAIM**

The ornamental design for a valve flush tool, as shown and described.

DESCRIPTION

FIG. 1 is a top perspective view of a valve flush tool embodying my new design;

FIG. 2 is a bottom perspective view thereof;

FIG. 3 is a top plan view thereof;

FIG. 4 is a bottom plan view thereof;

FIG. 5 is a front elevational view thereof;

FIG. 6 is a rear elevational view thereof;

FIG. 7 is a right-side elevational view thereof, the left-side elevational view being a mirror image; and,

FIG. 8 is a sectional view taken along the line 8-8 from FIG. 3.

1 Claim, 6 Drawing Sheets(56)
